UNITED STATES PATENT OFFICE.

ROBERT M. GALLOWAY AND PAUL C. BURTON, OF RICHMOND, INDIANA, ASSIGNEES
TO THE NATIONAL AUTOMATIC TOOL COMPANY, OF RICHMOND, INDIANA, A COR-
PORATION OF INDIANA.

DRILLING MACHINE.

Application filed September 7, 1923. Serial No. 661,448.

To all whom it may concern:

Be it known that we, ROBERT M. GALLOWAY and PAUL C. BURTON, citizens of the United States, residing at Richmond, in the county of Wayne and State of Indiana, have invented certain new and useful Improvements in Drilling Machines, of which the following is a specification.

This invention relates to improvements in drilling machines and its purpose is to provide improved means for moving the drill head on its support. The principal object of the invention is to provide means for effecting a rapid movement of the drill head during its non-working stroke and for automatically throwing into operation the power feed mechanism which advances the drill head after the cutting tools have been brought into proximity with the surface of the work. An improved feature of the invention is the provision of means for effecting the rapid traverse of the drill mechanism without the necessity of disconnecting the power feed mechanism which advances the drill head during the working stroke. A further object is to provide a motor operated rapid traverse mechanism comprising means for arresting the operation of the motor at predetermined intervals in the operation of the machine, the order of operations of the feed mechanism and the rapid traverse mechanism being regulated entirely by the motor control. Other objects relate to various features of construction and arrangement which will appear more fully hereinafter.

The nature of the invention will be understood from the following specification taken with the accompanying drawings in which one embodiment is illustrated. In the drawings, Fig. 1 shows a side elevation of a drilling machine embodying the present invention; Fig. 2 shows an enlarged side elevation of the drill head with adjacent parts of the operating mechanism; Fig. 3 shows a horizontal section taken on the line 3—3 of Fig. 2, illustrating a top plan view of the drill head and associated parts of the machine; Fig. 4 shows a detailed sectional view on the line 4—4 of Fig. 3; Fig. 5 shows a detailed section on the line 5—5 of Fig. 3; Fig. 6 shows a detailed vertical section taken on the line 6—6 of Fig. 5; Fig. 7 shows a longitudinal section taken

on the line 7—7 of Fig. 6; Fig. 8 shows a side elevation of the switch by which the operation of the rapid traverse motor is controlled; Fig. 9 shows an end elevation of the switch, looking toward the right as viewed in Fig. 8; Fig. 10 shows a sectional view taken on the line 10—10 of Fig. 8; Fig. 11 shows a sectional view taken on the line 11—11 of Fig. 8; and Fig. 12 shows a top plan view of the left end of the switch, as viewed in Fig. 8.

As illustrated in the drawings, the improved drilling machine comprises a supporting base 20, having mounted thereon a hollow vertical standard 21 adapted to carry the principal parts of the drill mechanism. This standard is provided on one side with vertical guide flanges 22 which are adapted to engage the vertical guideways 23 formed on the lateral extension 24 of the drill head 25. The part 24 of the drill head has plates 26 secured thereto by bolts 27 to overlap the guide flanges 22, thus locating the drill head securely on the supporting standard and permitting the vertical movement thereof. The drill head is connected to a cable 28 which extends over a pulley 29 mounted in a slot in the upper part of the standard on a shaft 30, and a suitable counterweight 31 is connected to the other end of the cable 28 within the hollow standard 21, thus minimizing the work which must be done to move the drill head along its vertical guideway.

The drill head 25 is provided with a plurality of drill spindles 33, only two of which are illustrated, and these drill spindles are actuated by suitable gears and pinions located within the drill head and driven from above through a vertical drive shaft 34. This shaft is driven by bevel gears located in the gear casing 35 which is mounted on the upper end of the standard 21 and these gears are in turn actuated by suitable drive mechanism located in the transmission casing 36 containing change speed gears which are operated by a lever 37. The transmission mechanism within the casing 36 is driven by a shaft 38 having fixed thereon a pulley 39 which in turn is actuated by a belt 40. This belt is driven by a pulley 41 fixed on the shaft 42 which is journaled in bearings carried by the standard 21 and the

bracket 43 mounted on the base 20. Another pulley 44 is fixed on the shaft 42 adjacent to the pulley 41 and an idler pulley 45 is rotatably mounted on the shaft adjacent to the pulley 44. A driving belt actuated by a motor or line shaft is adapted to engage the pulleys 44 and 45 and to be passed from one to the other by means of the shifting fork 46 which is slidably mounted on the rod 47 extending between the bracket 43 and the standard 41. The fork 46 carries arms 48 adapted to extend on opposite sides of the drive belt and the fork is shifted on the rod 47 by means of a crank 49 which actuates a lever 50 connected by a link 51 to the fork. The foregoing features of construction are common in drilling machines and do not in themselves constitute a part of the present invention.

20 The drill head 25 is moved vertically on the standard 21 by means of a rack bar 54 mounted on the side of the standard between the guide flanges 22 and adapted to be engaged by a pinion 55 mounted on the horizontal shaft 56 which is journaled in bearings carried by the lateral extension 24 of the drill head. The shaft 56 extends through the wall of the part 24 of the head and is journaled in the end wall 57^a of a casing 57 which is secured to the side of the head. The end of the shaft 56 has a gear 58 keyed thereon within the casing 57 and this gear is driven by a pinion 59 formed integrally with the shaft 60 which is journaled in bearings 61 and 62 carried by the end walls of the casing, as shown particularly in Fig. 7. The longitudinal movement of the shaft 60 away from the bearing 61 is prevented by a collar 63 which is pinned to the shaft adjacent to the bearing 62. A circular plate 64 is mounted on the shaft 60 adjacent to the pinion 59, this plate serving as a spacer between the pinion and the worm wheel 65 which is rotatably mounted on the shaft and adapted to be driven by a worm 66 which is keyed on the vertical power driven shaft 67. This shaft extends upwardly at the side of the column or standard 21 and is connected at its lower end through a universal joint 68 with the shaft 69. This shaft is driven by suitable gearing mechanism located in the casing 70 and connected to the shaft 42 which is driven by the belt from a line shaft or a motor.

50 Suitable change speed mechanism is located in the casings 71 and 72, this mechanism being operated by the levers 73 and 74 to secure the desired speed of rotation of the shaft 67. The worm wheel 65, which is driven constantly by the worm 66 on the shaft 67, has a clutch member 75 rotatably mounted on the enlarged portion 65^a of the hub of the worm wheel. A circular plate 76 is secured to the side of the clutch member 75 to space it from the worm wheel 65 and the side face of the clutch member is provided, within the bore of the plate 76 and outwardly of the hub of the worm wheel, with a series of ratchet teeth 77 adapted to be engaged normally by the clutch pins 78 which are slidably mounted in apertures 79 extending through the worm wheel 65. These clutch pins are provided with sockets which have mounted therein the coil springs 80, the opposite ends of the springs bearing against the plate 64 so that the pins are forced into engagement with the ratchet teeth 77. The clutch member 75 is normally rotated by the worm wheel 65 due to the engagement of the clutch pins with the ratchet teeth 77 but the clutch member 75 may be rotated at a higher speed than and in the same direction as the worm wheel, whereupon the clutch teeth will slide over the inclined end faces of the clutch pins 78 and these pins will merely reciprocate in the holes 79 in the worm wheel. The clutch member 75 is retained on the enlarged hub of the worm wheel by means of a collar 81 which is secured thereto by the cap screws 82, the collar being mounted on the reduced portion 65^b of the hub.

55 The clutch member 75 is provided on the side thereof opposite the ratchet teeth 77 with clutch teeth 85 adapted to be engaged by other clutch teeth 86 formed on the clutch member 87. The member 87 is splined on a sleeve 88 by means of a key 89 and the sleeve is in turn secured to the shaft 60 by means of a key 90. The clutch member 87 is recessed inwardly from the clutch teeth 86 to receive a washer 92 which is mounted on the reduced hub 65^b of the worm wheel and this washer is engaged by plungers 93 mounted in holes 94 which are formed in the hub of the worm wheel so that the coil springs 95 mounted between the plungers and the plate 64 serve normally to force the clutch member 87 away from the clutch member 75 with the resulting disengagement of the clutch teeth 85 and 86. The movement of the clutch member 87 away from the clutch member 75 is limited by the cam carrier 100 which is mounted on the reduced portion 60^a of the shaft 60. This cam carrier is provided with a plurality of notches 101 having located therein the cams 102 which are pivoted on transverse pins 103. The cams are provided with projections 104 adapted to engage the face 87^a of the clutch member 87 and with other projections 105 extending outwardly from the cam carrier to coact with the inclined face 107 of the clutch spool 108. The clutch spool is slidably and rotatably mounted on a sleeve 109 which is secured on the shaft 60 adjacent to the cam carrier 100 and when the spool is moved longitudinally toward the cam carrier the conical surface 107 engages the pro-

- jections 105 of the cams and forces them outwardly with the result that the opposite projections 104 move the clutch member 87 into engagement with the clutch member 75. The clutch spool 108 is moved longitudinally by means of pins 110 and 111 engaging the annular groove 112, the pins being carried by the arms of a yoke 113 which is pivotally mounted on a bolt 114 extending through and secured in the upper and lower walls of the casing 57. The upper pin 111 extends above the boss at the end of the yoke and is shouldered and threaded at its upper end to be engaged by a nut 115 and a washer 116. The pins 110 and 111 are pressed into the holes in the arms on the yoke and the projecting portion of the pin 111 serves as the operating member for moving the yoke 113 on its pivot and thereby reciprocating the clutch spool 108.
- The clutch yoke 113 is operated by means of a worm carrier 120 which is rotatably engaged and supported by a shaft 121 journaled in bearings 122 and 122^a carried by the walls of the casing 57. The worm carrier has an arm 120^a adapted to extend between the washer 116 and the adjacent arm of the yoke 113, the part 120^a having a notch 123 which engages the pin 111, the notch being elongated so that some movement of the cam carrier 120 may take place without causing a movement of the yoke 113, while the washer and yoke prevent the worm carrier from turning on the shaft 121. The worm carrier 120 is in the form of a yoke and a worm 125 is splined on the shaft 121 between the end bearings of the worm carrier, the end thrust of the worm being received by ball thrust bearings 126 which are mounted on the shaft at the ends of the worm. The projecting end of the shaft 121 has a gear wheel 127 fixed thereon and arranged to mesh with an intermediate gear 128 which in turn is driven by a gear 129 secured on the shaft of an electric motor 130. The motor is mounted on the casing 57 and the intermediate gear 128 is mounted on a stub shaft 131 projecting from the end casing of the motor, as shown in Fig. 5. This motor is controlled by the switch mechanism hereinafter described.
- The main shaft 60 is driven from the worm 125 through intermediate connections having engagement with the bevel gear 135 which is rotatably mounted on the shaft 60 at the end of the sleeve 109. The hub 136 of the gear has clutch teeth 137 formed thereon to mesh with the clutch teeth 138 formed on the sliding clutch member 139. The clutch member 139 is splined on the shaft 60 and is provided with an annular groove 140 engaged by the pins 141 which project inwardly from the arms of a clutch yoke 142. The clutch members 136 and 139 are normally separated by a coil spring 143 which is mounted between the clutch members on the shaft 60, the clutch members being recessed to receive the spring. The movable clutch member 139 is actuated to engage the clutch member 136 by means of the rocker 144 which engages the cross bar 145 on the yoke 142, the yoke being pivoted on a bolt 146 which extends through and between the side walls of the casing. The rocker 144 is pivoted on a pin 147 which is secured in the hub 148 carried by the casing 57 and is prevented from dropping off the pin by the small cotter pin 149. The rocker 144 has a flat face 150 extending between the corners or projections 151 and when the rocker is in its normal position, the face 150 is adapted to extend transversely to the center line of the shaft 60 in full contact with the cross bar 145 of the clutch yoke. The rocker 144 is further provided with an operating arm 152 which normally extends in a direction transverse to the axis of the shaft 60 and it is provided at its end with a notch 154 adapted to be engaged by the pin 155 which projects downwardly from the worm carrier 120. When the worm carrier moves either to the right or the left, as viewed in Fig. 6, from its normal position, the rocker 144 is tilted so that one or the other of the projections 151 operates to move the cross bar 145 toward the left as viewed in Figs. 6 and 7, thereby bringing the clutch member 139 into engagement with the clutch member 136 and causing the shaft 60 to be driven by the bevel gear 135.
- The bevel gear 135 is in turn actuated by a bevel pinion 160 having an elongated hub 161 which is journaled in a sleeve 165. The sleeve 165, which forms a clutch member, is journaled in a bushing 167 secured in the hub 168 formed in the wall of the casing, and this sleeve or clutch member has keyed thereon a worm wheel 166 meshing with and driven by the worm 125 previously described. A pair of bushings 162 are pressed into the bore of the hub 161 of the bevel pinion 160 and these bushings form bearings for the pilot shaft 164. The worm wheel 166 bears against one end of the hub 168 and the other end of the hub is engaged by a collar 169 which has set screws 170 passing therethrough and entering the tapered recesses 170^a which are formed in the sleeve 165. These set screws may be adjusted in the recesses 170^a to vary the frictional engagement of the collar 169 and the worm wheel 166 upon the ends of the hub 168, thus regulating the resistance which must be overcome to turn the worm wheel 166, as hereinafter more fully explained. A fixed clutch member 175 is pinned on the pilot shaft 164 with the teeth thereof opposing the teeth of the clutch member 165 and between these two clutch members there is located a sliding clutch member 176 which is splined on the

elongated hub 161 of the bevel pinion 160. The sliding clutch member 176 has clutch teeth on its opposite end faces to engage the teeth of the clutch members 165 and 175 and 5 a stud 177 projects downwardly from the sliding clutch 176 to permit the manual operation thereof. When the clutch member 176 is moved into engagement with the clutch member 175 a driving connection is 10 formed between the shaft 164 and the hub 161 of the pinion 160 so that, if the clutches 136 and 139 are simultaneously engaged, the shaft 60 may be operated by the manual rotation of the hand wheel 181 secured on the 15 end of the shaft 164 beyond the bearing 182 in which the end of the pilot shaft is journaled. The bearing 182 is formed on a bracket 180 and a collar 183 is pinned on the shaft 164 at the end of the bearing opposite 20 the hand wheel to prevent the longitudinal movement of the pilot shaft. When the clutch member 176 is moved into engagement with the clutch sleeve 165, a driving connection is formed between the worm wheel 166 25 and the bevel pinion 160, so that if the clutch members 136 and 139 are simultaneously engaged, the shaft 60 may be driven by the electric motor 130 through the worm 125 and the worm wheel 166. The sliding clutch 30 member 176 thus permits either a manual or a motor driven operation of the main shaft 60 through which the head 25 is raised and lowered on the column or standard 21 and the arrangement is such that only one 35 method of operation is capable of being employed at one time.

The electric motor 130 which is employed for effecting the rapid movement of the drill head 25 is operated by an electric circuit 40 comprising electric conductors leading thereto through the conduit 185. This conduit leads from a junction-box 186 into which the feed wires are conveyed to the vertical conduit 187. The circuit thus established 45 to the motor is controlled by a switch 188, the connections to which are made from the junction-box 186 through the conduit 189. The switch 188 comprises a casing 190 lined with suitable insulating material 191 and 50 closed by a detachable cover 192. A shaft 195 is journaled in bearings 196 carried by the end walls of the casing and this shaft has fixed thereon a drum 197 of insulating material carrying contact rings 198 which 55 are adapted to form connections between the contact fingers 199 mounted on the insulating bar 200 located in the upper part of the casing. The shaft 195 projects from the casing 193 and has fixed thereon a rocker 60 201. A coil spring 202 is mounted on the hub of this rocker with the extremities 203 and 204 thereof projecting upwardly on opposite sides of the lug 201^a which is formed on the rocker. The extremities of the spring 65 also project on opposite sides of another

lug 205^a which is formed on the upper end of a lever 205 by which the switch is operated. This lever is fixed on a shaft 206 which extends through the lower part of the casing 190, being journaled in bearings 70 207 carried by the end walls of the casing. The shaft 206 is operated by a crank arm 208 which is secured thereto at the end of the switch casing opposite the lever 205, and this crank arm is pivotally connected with a switch link 210 which extends along the side of the drill head 25 as illustrated in Fig. 1. The other end of this switch link is pivotally connected to a bell crank lever 211 which is pivoted on the bracket 180. The lever 211 has a projecting handle 212 which may be engaged by the operator to effect the manual operation of the switch mechanism but the switch is adapted to be operated, during the automatic operation of the machine, by means of trip dogs adapted to be engaged by a roller 215 which is rotatably mounted on the lever 205 as shown in Fig. 8. When the lever 205 is moved toward the right as viewed in Fig. 9, either by the engagement of a dog with the roller 215 or by the manual operation of the switch link 210, the lug 205^a engages the end 204 of the spring 202 and thereby carries with it the rocker 201 until the lug 217 on the rocker 95 is engaged by the lug 216 on the lever. A further motion of the lever 205 in the same direction continues to carry the end 204 of the spring with it, while the lug 216 slides under the lug 217, thereby winding up the 100 spring, due to the fact that the end 203 of the spring is held by the lug 201^a of the rocker. When the lug 216 is moved through the required distance, the lug 217 passes between the lugs 216 and 216^a and the spring 105 202 then turns the rocker and the shaft 195 with the result that the contact rings 198 are brought into contact with the contact fingers 199. When this is accomplished the 110 energy of the spring is exhausted and the contact rings remain in engagement with the fingers until the lever 205 is moved the required distance in the reverse direction. A further motion of the lever 205 in the same direction, after the circuit has been closed, 115 is prevented by the engagement of the lug 205^a with a stationary lug 218 formed on the end wall of the casing. A similar lug 219 limits the movement of the lever 205 in the reverse direction. To bring the contact rings 198 out of engagement with the fingers 199, the lever 205 is moved in the opposite direction, whereupon the lug 205^a engages the end 203 of the spring and carries the 120 rocker with it until the end of the lug 217 strikes on the under face of the lug 216 and stops the motion of the rocker while the lug 216 slides over the lug 217 until a point is 125 reached where the rocker is free to return to its original position under the influence 130

of the spring which is partially wound up while the lugs 216 and 217 are in sliding contact with each other. When the lever 205 is moved in the reverse direction, that is, toward the left from the neutral position illustrated in Fig. 9, the operation is reversed and the lugs 216^a and 217^a control the action of the spring in permitting a quick release of the rocker to move the contact rings into engagement with the fingers, thereby establishing a circuit through the motor in the reverse direction. By means of this construction the circuit of the motor is broken or closed almost instantaneously regardless of the angular velocity of the operating lever 205 which may be moved very slowly in some instances.

The switch 188 is actuated automatically to control the operation of the motor 130 by means of a plurality of trip dogs which are adjustably mounted on the vertical trip rod 225 mounted in brackets 226 secured to the side of the standard 21. When the head 25 is being moved downwardly by the rapid traverse mechanism, the rapid movement of the drill continues until the drills or other cutting tools are brought into proximity of the work, whereupon the roller 215 carried by the operating arm 205 of the switch engages the trip dog 228 which is carried by a block 229 adjustably secured to the trip rod 225 by means of a set screw 230. This trip dog throws the switch into neutral position and arrests the operation of the motor 130 after which the head continues to move downwardly at a slow rate of speed under the action of the power feed mechanism. When the drills or other cutting tools have passed through the work, the roller 215 on the switch arm 205 engages another dog 231 carried by the block 232 which is adjustably mounted on the trip rod 225 by means of a set screw 233. This results in the reversal of the motor 130 which then moves the head upwardly at a rapid rate until the roller 215 of the switch arm 205 engages another trip dog 234 carried by the block 235 which is adjustably mounted on the trip rod by means of a set screw 236. The dog 234 throws the switch into neutral position and stops the motor after which a limited continued movement of the head, due to its momentum, causes the roller 215 to engage another trip dog 237 which is carried by the block 238 adjustably mounted on the trip rod 225 by means of the set screw 239. The dog 237 again reverses the circuit of the motor 130 so that the head is again moved downwardly at a rapid rate.

Although the motor 130 may be started or stopped at any time by actuating the switch 188 through the switch rod 210 and the handle 212, and although the rapid traverse mechanism may be arrested at any time by shifting the clutch 176, the reversal of the

circuit of the motor 130 and the succession of upward and downward movement of the drill head 25 takes place automatically during the ordinary operation of the machine. Assuming that the drill head is at the top of the stroke, the operator starts the machine by shifting the clutch 176 toward the left, as viewed in Figs. 1 and 5, to form a driving connection between the worm wheel 166 and the hub 161 of the bevel pinion 160 and the circuit of the motor 130 is then closed by operating the switch 188 through the proper movement of the handle 212. At this stage of the operation of the machine, the clutch members 136 and 139 are engaged as herein-after more fully explained, and when the circuit of the motor 130 is closed, the first effect is to produce an end thrust in the worm 125 toward the left as viewed in Figs. 6 and 7, this end thrust being produced by reason of the angle of the worm threads engaging the spaces between the teeth of the worm wheel 166. As previously pointed out, the collar 169 mounted on the clutch 165 can be adjusted by means of the screws 170 to vary the frictional engagement of the collar and the worm wheel upon the hub 168 and this frictional resistance is adjusted so that more linear force is required on the pitch line of the worm wheel to turn it against this frictional resistance than is required to move the worm 125 together with the worm carrier 120 and the parts affected by their motion. The initial torque of the worm 125 operates, therefore, to move the worm and the worm carrier toward the left, as viewed in Figs. 6 and 7, until the left end of the worm carrier 120 meets the face of the boss carrying the bearing 122. The worm carrier then remains in this position and the worm 125 then drives the worm wheel 166 and operates the train of mechanism for effecting the rapid downward movement of the drill head 25. The movement of the worm 125 and the worm carrier 120 toward the left, as viewed in Figs. 6 and 7, tilts the rocker 144 so that when the carrier is in its extreme left position, the clutch members 136 and 139 are maintained in engagement by the pressure of the rocker 144 on the cross bar 145 of the clutch yoke 140. The movement of the worm carrier 120 toward the left, as viewed in Figs. 6 and 7, also tilts the clutch yoke 113 due to the engagement of the arm 120^a of the carrier with the pin 111. This causes the clutch spool 108 to move the cams 102 outwardly, thereby causing the clutch member 87 to engage the clutch member 75. The clutch member then rotates rapidly, at a greater speed than the worm wheel 65, while the ratchet teeth click over the ends of the clutch pins 78. When the ends of the drills have been brought into proximity with the surface of the work, the motor 130 is stopped by the

action of the trip dog 228 engaging the roller on the switch arm 205 and the continuously rotating worm wheel 65 then picks up the clutch member 75 and rotates it at a relatively slow speed adapted to effect the desired slow movement of the drill head 25 during the operation of drilling. The clutch members 75 and 87 being still engaged, the motion of the clutch member 75 is transmitted to the shaft 60 to effect this desired slow movement. The clutch members 136 and 139 being also still engaged, the shaft 60 drives the bevel pinion 160 at a slow speed in the same direction that it was rotating during the rapid motion of the drill head. Since the worm wheel 166 is unable to drive the worm 125 and the motor 130, the slow rotation of the bevel pinion 160 merely produces an end thrust on the worm 125, toward the right as viewed in Figs. 6 and 7, which results in a shifting of the cam carrier 120 toward the right until the flat face 150 of the rocker 144 reaches a position transverse to the axis of the shaft 60, in contact with the cross bar 145 of the yoke 142, in which position of the rocker, the clutch members 136 and 139 are fully disengaged by the action of the coil spring 143. The rotation of the bevel pinion 160 and the worm wheel 166 is then arrested. The motion of the cam carrier 120 toward the right, sufficient to effect the disengagement of the clutch members 136 and 139, does not affect the yoke 113 and the clutch spool 108 because the elongated slot 123 in the arm 120^a permits the necessary movement of the worm carrier without causing any movement of the pin 111. The clutch members 87 and 75 therefore remain in engagement while the drill head continues its slow downward movement. When the drills have passed through the work, the motor 130 is reversed by the dog 231 and the initial reverse operation of the motor sets up an end thrust in the worm 125 toward the right, as viewed in Figs. 6 and 7, thus causing a further movement of the worm carrier toward the right until it engages the end of the boss which carries the bearing 122^a, whereupon the motion of the worm carrier is arrested and the torque of the motor transmitted to the worm 125 is then applied in overcoming the frictional resistance of the collar 169 and the worm wheel 166 upon the hub 168, with the result that the worm wheel 166 is driven in a direction adapted to effect an upward movement of the drill head. This upward movement begins as soon as the worm carrier 120 reaches its extreme right-hand position because the movement of the worm carrier tilts the rocker 144 until the lower point 151 of the rocker moves the clutch members 136 and 139 into engagement with each other, as shown in Fig. 6, thereby establishing a driving connection between the bevel gear 135 and the shaft 60. At the same time that the clutch members 136 and 139 are engaged by the movement of the worm carrier 120 toward the right, the arm 120^a of the worm carrier tilts the yoke 113 and shifts the clutch spool 108 so that the clutch members 75 and 87 are permitted to disengage under the influence of the plungers 93 and springs 95. The drill head then continues its upward movement until the motor 130 is stopped and reversed by the action of the trip dogs 234 and 237. When this reversal takes place, with the drill head 25 in the desired upper position, the worm carrier 120 is in its extreme right-hand position, as shown in Fig. 6, and the clutch members 136 and 139 are still engaged, so that the drill head immediately begins to move rapidly downward again, setting up an end thrust in the worm 125 toward the left and causing the whole cycle of operations to be repeated as before. The succession of operations of the rapid traverse mechanism and the power feed mechanisms are thus brought about automatically and the reversals in the direction of movement of the drill head may be caused to occur at any desired points in its travel through the adjustment on the trip rod 225 of the trip dogs by which the circuit of the motor 130 is controlled. An important advantage of the invention is that the succession of operations of the power feed mechanism and the rapid traverse mechanism is controlled entirely by the regulation of the circuit of the electric motor, the engagement of the clutches being brought about automatically in response to the changes in the circuit condition of the motor. The mechanism is therefore capable of very fine adjustment and operates to effect a great saving of time in the operation of drilling machines or other machines to which the invention may be applied.

Although a single form of machine has been shown and described for purposes of illustration, it will be understood that the invention may be constructed in various other embodiments without departing from the scope of the appended claims.

We claim:

1. In a machine of the class described, a movable head, slow power feed mechanism for moving said head, rapid traverse mechanism for moving said head, means for controlling said rapid traverse mechanism and means actuated upon starting the traverse mechanism in one direction for operatively connecting the slow feeding mechanism to the head and upon starting the traverse mechanism in a reverse direction for disconnecting the slow power feed mechanism from the head.
2. In a machine of the class described, a movable head, slow power feed mechanism for moving said head, rapid traverse mecha-

nism for moving said head, electrically actuated, means for controlling said rapid traverse mechanism, and means controlled by the starting of said rapid traverse mechanism for controlling the operation of said slow power feed mechanism.

3. In a machine of the class described, a movable head, slow power feed mechanism for moving said head, rapid traverse mechanism for moving said head, means for connecting said rapid traverse mechanism to move said head, means for arresting the operation of said rapid traverse mechanism, and means actuated by the operation of said slow power feed mechanism for disconnecting said rapid traverse mechanism.

4. In a machine of the class described, a movable head, slow power feed mechanism for moving said head, rapid traverse mechanism for moving said head, and means actuated by said rapid traverse mechanism for establishing an operative connection of said feed mechanism with said head, said connection being adapted to permit simultaneous operation of said rapid traverse mechanism.

5. In a machine of the class described, a movable head, slow power feed mechanism for moving said head, rapid traverse mechanism for moving said head, means actuated by said rapid traverse mechanism for establishing an operative connection of said slow feed mechanism with said head, said connection being adapted to permit simultaneous operation of said rapid traverse mechanism, means for reversing said rapid traverse mechanism, and means actuated by said reversal for breaking the operative connection of said slow power feed mechanism with said head.

6. In a machine of the class described, a movable head, slow power feed mechanism for moving said head, rapid traverse mechanism for moving said head, a motor for driving said rapid traverse mechanism, and means actuated by the initial operation of said motor for controlling the operation of said slow power feed mechanism and said rapid traverse mechanism.

7. In a machine of the class described, a movable head, slow power feed mechanism for moving said head, rapid traverse mechanism for moving said head, a motor, a worm driven by said motor, said worm having a limited longitudinal movement in response to the actuation of said motor, and means actuated by the longitudinal movement of said worm for controlling the operation of said rapid traverse mechanism by said worm and the operation of said slow power feed mechanism.

8. In a machine of the class described, a movable head, slow power feed mechanism for moving said head, rapid traverse mechanism for moving said head, a motor, a worm driven by said motor and adapted to actuate

said rapid traverse mechanism, said worm having a limited longitudinal movement in response to the initial actuation of said motor, means actuated by the movement of said head for starting and stopping said motor, and means actuated by the longitudinal movement of said worm for controlling the operation of said slow power feed mechanism in the intervals between the operations of said rapid traverse mechanism.

9. In a machine of the class described, a movable head, a shaft having a driving connection with said head, slow power feed mechanism, rapid traverse mechanism for raising and lowering said head, and means actuated by the starting of said rapid traverse mechanism for lowering the head to establish a driving connection between said slow feed mechanism and said shaft.

10. In a machine of the class described, a movable head, an operating shaft having a driving connection with said head, slow power feed mechanism for driving said operating shaft, rapid traverse mechanism, means for forming a driving connection between said rapid traverse mechanism and said operating shaft, and means actuated by said slow power feed mechanism for breaking said operative connection of said rapid traverse mechanism with said shaft.

11. In a machine of the class described, a movable head, an operating shaft having a driving connection with said head, slow power feed mechanism, means for connecting said slow power feed mechanism with said operating shaft, rapid traverse mechanism, means actuated by said rapid traverse mechanism for operating said connecting means, and means for arresting the operation of said rapid traverse mechanism, said connecting means being adapted to maintain the connection of said slow feed mechanism with said operating shaft after the operation of said rapid traverse mechanism has been arrested.

12. In a machine of the class described, a movable head, an operating shaft having a driving connection with said head, rapid traverse mechanism, means for driving said rapid traverse mechanism, and means actuated by the initial operation of said driving means for establishing a driving connection between said rapid traverse mechanism and said operating shaft.

13. In a machine of the class described, a movable head, an operating shaft having a driving connection with said head, rapid traverse mechanism, a motor for driving said rapid traverse mechanism, means for actuating said motor in either direction, and means actuated by the initial operation of said motor in either direction for establishing a driving connection between said rapid traverse mechanism and said operating shaft.

14. In a machine of the class described, a movable head, an operating shaft having a driving connection with said head, slow power feed mechanism, rapid traverse mechanism, means for driving said rapid traverse mechanism, means actuated by the initial operation of said driving means for forming a driving connection between said rapid traverse mechanism and said operating shaft, and means actuated by the operation of said operating shaft by said rapid traverse mechanism for forming a driving connection between said slow power feed mechanism and said operating shaft.
15. In a machine of the class described, a movable head, an operating shaft having a driving engagement with said head, slow power feed mechanism, rapid traverse mechanism, means for driving said rapid traverse mechanism, means actuated by the initial operation of said driving means for forming a driving connection between said rapid traverse mechanism and said operating shaft, and means actuated by the operation of said operating shaft by said rapid traverse mechanism for forming a driving connection between said slow power feed mechanism and said operating shaft, said last named connection being adapted to permit the continued operation of said rapid traverse mechanism in moving said head.
16. In a machine of the class described, a movable head, an operating shaft having a driving engagement with said head, slow power feed mechanism, rapid traverse mechanism, means for driving said rapid traverse mechanism, means actuated by the initial operation of said driving means for forming a driving connection between said rapid traverse mechanism and said operating shaft, and means actuated by the operation of said operating shaft by said rapid traverse mechanism for forming a driving connection between said slow power feed mechanism and said operating shaft, said last named connection being adapted to permit the continued operation of said rapid traverse mechanism in moving said head, means for arresting the operation of said driving means, and means actuated thereafter by the operation of said driving means, and means actuated thereafter by the operation of said operating shaft by said slow power feed mechanism with said operating shaft.
17. In a machine of the class described, a movable head, an operating shaft having a driving engagement with said head, slow power feed mechanism, rapid traverse mechanism, means for driving said rapid traverse mechanism, means actuated by the initial operation of said driving means for forming a driving connection between said rapid traverse mechanism and said operating shaft, means actuated by the operation of said operating shaft by said rapid traverse mechanism for forming a driving connection between said slow power feed mechanism and said operating shaft.
18. In a machine of the class described, a movable head, an operating shaft having a driving engagement with said head, slow power feed mechanism, rapid traverse mechanism, means for driving said rapid traverse mechanism, means actuated by the initial operation of said driving means for forming a driving connection between said rapid traverse mechanism and said operating shaft, means actuated by the operation of said operating shaft by said rapid traverse mechanism for forming a driving connection between said slow power feed mechanism and said operating shaft, said last named connection being adapted to permit the continued operation of said rapid traverse mechanism in moving said drill head, means for arresting the operation of said driving means, means actuated thereafter by the operation of said operating shaft by said power feed mechanism for breaking the connection of said rapid traverse mechanism with said operating shaft, means for operating said driving means in the reverse direction, means actuated by the initial reverse operation of said driving means for re-establishing the driving connection of said rapid traverse mechanism with said operating shaft and for breaking the driving connection of said feed mechanism with said operating shaft.
19. In a machine of the class described, a movable head, slow power feed mechanism for moving said head, rapid traverse mechanism for moving said head, a motor carried by the head for driving said rapid traverse mechanism, cam operative means actuated by the movement of said head for controlling the operation of said motor, and means actuated in response to the actuation of said motor for controlling the succession of oper-

- ations of said slow power feed mechanism and said rapid traverse mechanism in moving said head.
20. In a machine of the class described a movable head, slow power feed mechanism for moving said head, rapid traverse mechanism for moving said head, a rotating reversible motor for driving said rapid traverse mechanism, manually controlled means for starting said motor, means actuated by the initial movement of said motor for establishing a driving connection between said slow power feed mechanism and said head, and means actuated by the movement of said head for arresting the operation of said motor after a predetermined movement of said head.
21. In a machine of the class described, a movable head, slow power feed mechanism for moving said head, rapid traverse mechanism for moving said head, a reversible electric motor for driving said rapid traverse mechanism, manually controlled means for starting said motor, means actuated by the initial movement of said motor for establishing a driving connection between said slow power feed mechanism and said head, means actuated by the movement of said head for arresting the operation of said motor after a predetermined movement of said head, and means actuated thereafter by the operation of said slow power feed mechanism for disconnecting said rapid traverse mechanism.
22. In a machine of the class described, a movable head, slow power feed mechanism for moving said head, rapid traverse mechanism for moving said head, a motor for driving said rapid traverse mechanism, manually controlled means for starting said motor, means actuated by the initial movement of said motor for establishing a driving connection between said slow power feed mechanism and said head, means actuated by the movement of said head for arresting the operation of said motor after a predetermined movement of said head, means actuated thereafter by the operation of said slow power feed mechanism for disconnecting said rapid traverse mechanism, means actuated by the movement of said head for reversing the operation of said motor, and means actuated by the reverse operation of said motor for breaking the driving connection of said slow power feed mechanism with said head and re-establishing the driving connection of said rapid traverse mechanism with said head.
23. In a machine of the class described, a movable head, an operating shaft having a driving connection with said head, a worm wheel rotatively mounted on said operating shaft, a slow power feed shaft, a worm fixed on said feed shaft and meshing with said worm wheel, a clutch member rotatively mounted adjacent said worm wheel, said clutch member having ratchet teeth, clutch pins resiliently mounted in said worm wheel to engage said ratchet teeth, a second clutch member having a driving engagement with said operating shaft, and means for moving said second clutch member into engagement with said first named clutch member for effecting slow feeding movement of the head.
24. In a machine of the class described, a movable head, an operating shaft having a driving connection with said head, a worm wheel rotatively mounted on said operating shaft, a slow power feed shaft, a worm fixed on said feed shaft and meshing with said worm wheel, a clutch member rotatively mounted adjacent said worm wheel, said clutch member having ratchet teeth clutch pins resiliently mounted in said worm wheel to engage said ratchet teeth, a second clutch member having a driving engagement with said operating shaft and adapted to be moved in engagement with said first named clutch member, rapid traverse mechanism for driving said operating shaft, and means controlled by said rapid traverse mechanism for actuating said second clutch member.
25. In a machine of the class described, a movable head, an operating shaft having a driving connection with said head, a worm wheel rotatively mounted on said operating shaft, a slow power feed shaft, a worm fixed on said feed shaft and meshing with said worm wheel, a clutch member rotatively mounted adjacent said worm wheel, said clutch member having ratchet teeth clutch pins resiliently mounted in said worm wheel to engage said ratchet teeth, a second clutch member having a driving engagement with said operating shaft and adapted to be moved in engagement with said first named clutch member, a clutch spool slidably mounted on said operating shaft, and cams adapted to be actuated by said spool for moving said second clutch member, and means for moving said spool to control the slow feeding movement of the head.
26. In a machine of the class described, a movable head, an operating shaft having a driving connection with said head, a worm wheel rotatively mounted on said operating shaft, a slow power feed shaft, a worm fixed on said feed shaft and meshing with said worm wheel, a clutch member rotatively mounted adjacent said worm wheel, said clutch member having ratchet teeth clutch pins resiliently mounted in said worm wheel to engage said ratchet teeth, a second clutch member having a driving engagement with said operating shaft and adapted to be moved in engagement with said first named clutch member, a clutch spool slidably mounted on said operating shaft, cams

adapted to be actuated by said spool for moving said second clutch member, rapid traverse mechanism for actuating said operating shaft, and means controlled by said 5 rapid traverse mechanism for moving said spool.

27. In a machine of the class described, a movable head, an operating shaft having a driving connection with said head, slow 10 power feed mechanism, a pair of clutch members for establishing a driving connection of said power feed mechanism with said operating shaft, a motor, means including a pair of clutch members for forming a driving 15 connection between said motor and said operating shaft, a traveling member adapted to be moved by the actuation of said motor, and means actuated by said traveling member for controlling the operation of each 20 pair of said clutch members.

28. In a machine of the class described, a movable head, an operating shaft having a driving connection with said head, slow power feed mechanism for moving said motor, a pair of clutch members for forming a driving connection between said power mechanism and said operating shaft, a pilot shaft, a gear fixed on said pilot shaft, a motor, a worm driven by said motor, a worm 25 wheel meshing with said worm, means including a pair of clutch members for forming a driving connection between said worm wheel and said pilot shaft, a gear meshing with said first named gear and rotatively mounted on said operating shaft, a third 30 pair of clutch members for forming a driving connection between said operating shaft and said second named gear, and a traveling member actuated by said worm for controlling 35 the operation of said first and third named pairs of clutch members.

29. In a machine of the class described, a movable head, an operating shaft having a driving connection with said head, slow 40 power feed mechanism for moving said motor, a pair of clutch members for forming a driving connection between said power mechanism and said operating shaft, a pilot shaft, a gear fixed on said pilot shaft, a motor, a worm governed by said motor, a worm wheel meshing with said worm, means including a pair of clutch members for forming a driving connection between said worm wheel and said pilot shaft, a gear meshing 45 with said first named gear and rotatively mounted on said operating shaft, a third pair of clutch members for forming a driving connection between said operating shaft and said second named gear, a traveling member actuated by said worm, and a connection 50 from said traveling member for operating said first and third named pairs of clutch members.

30. In a machine of the class described, a movable head, an operating shaft having

a driving connection with said head, slow power feed mechanism for moving said motor, a pair of clutch members for forming a driving connection between said power mechanism and said operating shaft, a pilot 70 shaft, a gear fixed on said pilot shaft, a motor, a worm governed by said motor, a worm wheel meshing with said worm, means including a pair of clutch members for forming a driving connection between said worm wheel and said pilot shaft, a gear meshing with said first named gear and rotatively mounted on said operating shaft, a third pair of clutch members for forming a driving connection between said operating shaft 75 and said second named gear, a traveling member actuated by said worm, and a connection from said traveling member for operating said first and third named pairs of clutch members, said connections being 80 adapted to permit the disconnection of said third named pair of clutch members before the disconnection of said second named pair of clutch members takes place.

31. In a drilling machine, the combination comprising a movable head; a slow power feed mechanism for moving the head; a rapid traverse mechanism for moving said head; means for controlling said rapid traverse mechanism; and means actuated upon starting the rapid traverse mechanism in one direction to operatively connect the slow power feed mechanism to the head and upon starting the rapid traverse mechanism in a reverse direction to disconnect the slow feed mechanism.

32. In a drilling machine, the combination comprising a movable head; a slow power feed mechanism for moving the head; a rapid traverse mechanism for moving said head; a motor for operating the rapid traverse mechanism; and means operated by the motor rotating in one direction for operatively connecting the slow feed mechanism to move the head and operated by the motor rotating in a reverse direction to disconnect the slow feed mechanism.

33. In a drilling machine, the combination comprising a movable head; a slow power feed mechanism for moving the head; a rapid traverse mechanism for moving the head; a motor rotatable in a forward and in a reverse direction for operating the rapid traverse mechanism, a clutch for connecting the slow feed mechanism to move the head; and means for operating said clutch in accordance with the direction of rotation of the motor.

34. In a drilling machine, the combination comprising a movable head; a slow power feed mechanism for moving the head; a rapid traverse mechanism for moving the head, said traverse mechanism being carried by the head; a motor carried by the head and rotatable in a forward and in a reverse

direction for operating the rapid traverse mechanism; a clutch for controlling the slow feed mechanism; and means for controlling said clutch in accordance with the direction 5 of rotation of the motor.

35. In a drilling machine, the combination comprising a movable head; slow power feed mechanism for moving said head; rapid traverse mechanism for moving said head; a 10 motor rotatable in a forward and in a reverse direction for operating the rapid traverse mechanism; means for operating the motor in accordance with the movement of the head; and means for operating the slow

feed mechanism in accordance with the direction of rotation of the motor. 15

36. In a drilling machine, the combination comprising a movable head; slow power feed mechanism for moving said head; rapid traverse mechanism for raising and lowering said head; means for controlling the rapid traverse mechanism according to the movement of the head; and means operated upon starting the traverse mechanism in one direction for connecting the slow power feed 20 mechanism to the head. 25
